UNITED STATES PATENT OFFICE.

WALTER E. SIMONS, OF DUBLIN, CANADA.

TELEGRAPH-KEY.

SPECIFICATION forming part of Letters Patent No. 558,617, dated April 21, 1896.

Application filed September 12, 1895. Serial No. 562,344. (No model.)

To all whom it may concern:

Be it known that I, WALTER E. SIMONS, of Dublin, in the county of Perth and Province of Ontario, Canada, have invented certain new and useful Improvements in Circuit-Closers for Telegraph-Keys, of which the following is a specification.

This invention relates to means for insuring the closure of a telegraph-key when the same is not in use; and it consists in the novel construction and combination of the parts hereinafter fully described and claimed.

In the drawings, Figure 1 is a side view, partly in section. Fig. 2 is a plan view, and Fig. 3 is an end view, of a telegraph-key constructed according to this invention. Fig. 4 is a cross-section taken on line α in Fig. 2.

A is the base of the instrument.

B is the operating-lever supported by the set-screws 2 and pivots 3, and 4 is the ordinary front contact-point.

F is a spring circuit-closer secured at one end below the point 4 and in contact therewith. The free end of the spring F has a double eye I and a shoulder f' , which normally rests upon the top of the lever B, so as to close the circuit.

E is a trip-lever pivoted on the pin 5, projecting from the side of the lever F and having its front end bent upward and provided with a button f , which projects through the button 6 on the operating-lever. The rear end of the lever E is provided with a pin 7, which engages with the bushes 8 of insulating material carried by the double eye I.

J is a bracket secured to the base A, and a is a spring interposed between the rear end of the lever B and a thumb-screw 9, carried by the said bracket and operating to assist in pressing the rear end of the lever B downward.

When the button f is depressed, it raises the spring circuit-closer F off the lever B and holds it raised as long as the key is in use. When the button f is no longer depressed by the operator, the circuit-closer F descends on the lever B and closes the circuit. The spring a operates to prevent the rear end of the lever B from rising until the circuit-closer has been raised clear of the lever B. A guard 10 is provided for the lever E and may be formed integral with or secured to the lever B.

What I claim is—

The combination, with a telegraph-key provided with an operating-lever and a front contact-point; of a spring circuit-closer connected with the front contact-point and bearing downward on the said lever, a trip-lever pivoted to the operating-lever and having its rear end pivoted to and insulated from the free end of the circuit-closer, and a spring connected to the rear end of the operating-lever and operating to prevent it from rising until the circuit-closer has been moved out of contact with it, substantially as set forth.

WALTER E. SIMONS.
